(57) **CLAIM**

The ornamental design for a microwave oven with hood as shown and described.

DESCRIPTION

FIG. 1 is a top perspective view of the microwave oven with hood showing our design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof;

FIG. 9 is a bottom plan view of the microwave oven with hood shown in a first state of illumination;

FIG. 10 is a bottom plan view of the microwave oven with hood shown in a second state of illumination;

FIG. 11 is a bottom plan view of the microwave oven with hood shown in a third state of illumination;

FIG. 12 is a bottom plan view of the microwave oven with hood shown in a fourth state of illumination; and,

FIG. 13 is a top perspective view of the microwave oven with hood shown with the door in an open position.

The stippling represents illumination and forms no part of the claimed design. The process or period in which one state of illumination transitions to another state of illumination forms no part of the claimed design. The broken lines depict portions of the microwave oven with hood that form no part of the claimed design.
